DOLL EYES

Application filed August 24, 1927. Serial No. 215,108.

The invention forming the subject matter of this application relates to improvements in doll eyes which close when the doll is reclined and open when the doll is raised in an upright position.

The principal object of this invention is to provide a doll, the eyes of which may close instantaneously or gradually when the doll is reclined, according to the position of the doll when reclined.

It is the object of the invention to effect an instantaneous closing of the eyes of the doll when the doll is laid on one side thereof while laying down the doll on the other side thereof will necessitate the rocking of the doll to gradually close the eyes thereof.

The above and other objects in view will more readily appear as the description proceeds, although I show and describe a preferred embodiment of my invention, it is to be understood that changes as to the form, parts, the design and arrangement may be made within the scope of the appended claims without departing from the spirit of or sacrificing any of the advantages of the invention.

Referring to the annexed drawing, in which my invention is illustrated and which forms a part of this specification:

Figure 1 is a vertical section of a doll head embodying my invention,

Figure 2 is a transverse vertical section on the line 2—2 of Figure 1,

Figure 3 is a plan view of the doll head showing the clamping mechanisms, the top of the head being removed,

Figure 4 is a face view of the pendulum guide and the clamping means therefor,

Figure 5 is a sectional view of the pendulum guide taken along the line 5—5 of Figure 4.

In the drawing 1 indicates a doll head in the face wall of which are eye openings 2 in which are fitted eye balls 3. The backs of the eye balls 3 are secured to the ends of a transverse bar 4 by means of screws 5. The transverse bar 4 is pivotally supported in lugs 6 extending from a fastening plate 7. The plate 7 has a centrally located slot 8 adjacent to the end thereof for receiving a fastening screw 9 secured to a boss 10 which

latter protrudes inwardly from the face of the doll head. An arm 11 extends downwardly and is fixedly secured to the transverse bar 4 between the lugs 6. A pendulum 12 is secured to the lower end of the arm 11. When the pendulum 12 swings away from the face of the doll head it turns the arm 11 and thereby rotates the transverse bar 4 in the lugs 6, so that the eye balls 3 are turned in their openings 2 to simulate a child going to sleep or awaking.

A pin 13 descends from the pendulum 12. A pendulum guide denoted in its entity by the numeral 14 comprises a Y-shaped member 15 and a guide 16 depending therefrom and secured thereto by means of a screw 17. The guide 16 is bent so as to form a curvature, the concave side of which is bent toward the face portion of the doll head. The center of the curvature of the guide 16 is approximately on the axis of the transverse bar 4. The Y-shaped member 15 carries the clamp 18 at the end thereof, adjacent to the rear of the doll head. The clamp 18 is fastened thereto by means of a screw 19 bearing on the Y-shaped member 15. The bi-forked members of the Y-member 15 are denoted by the numeral 20, the ends thereof are cut so as to form tongues 21. The tongues 21 are bent downwardly thereby forming a wedge opening 22 for the engagement of the edge of the face portion of the doll head. The guide is firmly clamped in place by pressing the wedge opening 22 against the corner of the doll face by means of fastening the clamp member 18.

The guide member 16 has a straight slot 23 and a zig-zag slot 24 cut therein so that the straight and the zig-zag slots are one continuous opening in the guide 16 and are disposed side by side. The inside walls of the slots 23 and 24 are formed by an insert member 25 cut so that the outline of the insert member 25 is parallel with the other wall of the slots 23 and 24, said insert member is supported in position by means of a bridge member 26 reaching over from the outside wall of the guide 16 to the insert 25 and secured to the guide and to the insert member by means of screws 27.

The pin 13 extends into the slot and when the doll is held in an upright position the pin 13 is forced by the weight of the pendulum 12 to the lower extremity of the slot 23 and is guided by a beveled wall 28 so as to take up a position opposite the first turn of the zig-zag slot 24.

Looking at the face of the doll when the doll is laid down so that it is in a reclined position on the right side of the head the pin 13 is forced by the action of the pendulum 12 to travel on the bevel 28 into the straight slot 23 and to travel the full length of the straight slot 23 instantaneously, thereby closing the doll's eyes without necessitating the rocking of the doll. When the doll is raised again into the upright position the pin 13 guided by a bevel 29 on the upper corner of the insert member 25 follows the straight slot 23 and instantaneously opens the doll's eyes.

When the doll is reclined without turning the head to either side the pin 13 hits against the protrusion 30 disposed at the lower end of the insert member 25 opposite the bevel portion 28, and the eyes of the doll are kept open because the pin 13 rests upon said protrusion without engaging either one of said slots. In this case the doll is put asleep by rocking right and left alternately so that the pin 14 slides off the protrusion 30 into the first zig-zag slot 24 and by every rocking in opposite directions the pin 13 travels the full length of one-half of a zig-zag slot.

After the pin 13 travels the full length of the slot 24 it is rocked at the upper end thereof to the top of the straight slot 23 and the eyes of the doll are completely closed. When the doll is elevated again in the upright position the pin 13 travels the full length of the straight slot 23 instantaneously and the eyes of the doll open.

When the doll is laid down so as to be turned on the side toward the zig-zag slot 24, the pin 13 immediately engages the first portion of the slot 24 and the doll may be rocked to sleep as heretofore described.

It is apparent that the rocking of the doll from side to side in a reclined position causes the eye balls to gradually turn and produce a very accurate imitation of a child going to sleep. By means of the straight slots the awakening of the child is imitated more naturally than if the doll would have to be rocked awake. It is also evident that the use of the straight slot and the zig-zag slot is interchangeable and depends on which side the doll is laid down and that the movement of the eyes is fully controlled by the guiding slots 23, 24 and the pin 13.

Having thus described my invention, what I now claim as novel and desire to secure by Letters Patent is:

1. In combination with a doll having turn-
ably mounted opening and closing eyes, a pen-

dulum mounted on the eyeballs with freedom of lateral swinging movement, and an arcuate pendulum guide having a straight and a zig-zag slot disposed side by side therein for guiding the pendulum so as to cause the eyes to close when the doll is reclined on one side and to cause the eyes to be closed gradually by the rocking of the doll when the same is reclined on the other side, and to open the eyes without rocking when the doll is disposed in an upright position.

2. In combination with a doll having turnably mounted eyes therein, a pendulum connected with the eyes for turning the same, said pendulum having freedom of lateral swinging movement upon said mounting; and an arcuate pendulum guide having a zig-zag slot and a straight slot disposed side by side therein, said slots being disposed in operative relation to the pendulum so as to selectively guide the same.

3. In combination with a doll having opening and closing eyes, a pendulum mounted on the eyeballs for turning the same, and an arcuate pendulum guide having a straight slot and a zig-zag slot therein disposed side-by side said straight slot permitting unobstructed movement of the pendulum therein when the doll is reclined on one side thereby causing the pendulum to close the eyes of said doll promptly, said zig-zag slot guiding the movement of the pendulum in zig-zag upon rocking the doll when the doll is reclined on the other side, thereby causing the pendulum to close the eyes gradually, and means to direct the pendulum into said straight slot when the doll is raised to an upright position.

4. In combination with a doll having pivotally mounted opening and closing eyes, a pendulum, means for mounting said pendulum on the eyeballs with freedom of lateral swinging movement, a pendulum guide including a straight section and a curved section, the rear end of said straight section being clamped to the top of the rear wall of the doll head, tongues on the front end of the straight section resting on top of the front wall of the doll head so that said curved section rests inside the doll head, said curved section being centered substantially around the pivotal mounting of the eyeballs and having a zig-zag slot therein, engaged by the lower end of said pendulum when the doll is reclined on one side whereby the eyes are caused to close when the doll is rocked side-wise, and having a straight slot disposed on the side of said zig-zag slot and connected therewith, so as to be engaged by the lower end of the pendulum when the doll is reclined on the other side thereby causing the eyes to close instantaneously and causing said eyes to open when the doll is returned to an upright position.

5. In combination with a doll having open-

- ing and closing eyes, a pendulum for turning the eyes, being mounted on the eyeballs with freedom of lateral swinging movement, and an arcuate pendulum guide having a straight 5 and a zig-zag slot side by side therein for guiding the pendulum to cause the eyes to close when the doll is reclined on one side and to cause the eyes to close gradually by rocking the doll when the same is reclined on the 10 other side and to open the eyes when the doll is disposed in an upright position, and means to removably secure said pendulum guide to the head of the doll, in operative relation to said pendulum.
- 15 6. In combination with a doll having opening and closing eyes, a pendulum for turning the eyeballs, being mounted on the eyeballs with freedom of lateral swinging movement, an arcuate pendulum guide centered substantially around the pendulum mounting and an insert member secured to said pendulum guide so as to form therein a straight slot and a zig-zag slot, side by side, said straight slot guiding the pendulum when the doll is reclined on one side and said zig-zag slot guiding the pendulum when the doll is rocked laterally in a reclined position on the other side.
- 20 7. In combination with a doll having turnably mounted eyes therein, a pendulum connected with the eyes for turning the same, said pendulum having freedom of lateral swinging movement upon said mounting; an arcuate pendulum guide having a zig-zag 25 slot and a straight slot disposed side by side therein, said slots being disposed in operative relation to the pendulum so as to selectively guide the same, and means to removably clamp said guide to the head of the doll.
- 30 8. In combination with a doll having turnably mounted eyes therein, a pendulum connected with the eyes for turning the same, said pendulum having freedom of lateral swinging movement upon said mounting; 35 and an arcuate pendulum guide having a zig-zag slot and a straight slot disposed side by side therein, said slots being disposed in operative relation to the pendulum so as to selectively guide the same and communicat-
- 40 45 50 55 60 65 70 75 80 85 90 95 100 105 110 115 120 125 130
- ing with each other at the opposite ends thereof so as to direct said pendulum into the slot toward which the doll is reclined and so as to direct said pendulum into the straight slot after the eyes are closed.
- 55 9. In combination with a doll head having opening and closing eyeballs, a bar rotatably supported on the inside of said head for holding the eyeballs in place; a pendulum for rotating the bar, said pendulum being secured 60 to the bar with freedom of lateral swinging movement, an arcuate guide plate secured in said head so as to be centered around the bar; said guide plate having a straight slot and an arcuate slot therein, disposed side by side; the 65 end of the pendulum being slid able in said slots; said slots being so formed at an end thereof so as to direct the pendulum into the slot toward which the doll is reclined, the other ends of the slots being adapted to direct the pendulum into the straight slot after the eyeballs are turned to the closed position.
- In testimony whereof I affix my signature.
